UNITED STATES PATENT OFFICE.

WILLIAM HALTER, OF CLEVELAND, OHIO.

COMBINATION SOCKET AND ADAPTER.

1,336,431.

Specification of Letters Patent. Patented Apr. 13, 1920.

Application filed March 9, 1918. Serial No. 221,428.

To all whom it may concern:

Be it known that I, WILLIAM HALTER, citizen of the United States, residing at Cleveland, in the county of Cuyahoga and State of Ohio, have invented certain new and useful Improvements in Combination Sockets and Adapters, of which the following is a specification.

This invention relates to combination sockets and adapters for receiving electric circuit plugs or other connectors. The object of the invention is to provide a device of this kind so constructed as to receive interchangeably either the threaded base of a lamp, a threaded plug, or a rectangular or non-circular push plug, thereby enabling the same socket or receiver to serve interchangeably with various forms of connections to the lamp or other device to be supplied with current, and avoiding the use of intermediate adapters.

Further objects of the invention are in part obvious and in part will appear more in detail hereinafter.

In the drawings, Figure 1 represents a plan view, partly broken out and in section, illustrating one form of device embodying the invention; Fig. 2 is a sectional elevation on the line 2—2, Fig. 1; Fig. 3 is a side elevation of a non-circular push plug adapted for connection with the socket or receiver shown in Figs. 1 and 2; and Fig. 4 is an outside elevation of a threaded plug.

Referring to Figs. 1 and 2, my improved socket or adapter comprises a body portion 1 which may be formed of any suitable material, preferably insulating, such as porcelain, hard rubber, or composition material, and which is suitably constructed for securement to a support or in a recess of the wall. This body portion is provided with a cavity 2 designed to receive the plug or connector. Cavity 2 is of peculiar shape, having two oppositely disposed surfaces 3, which are interrupted portions of the same cylindrical surface, the material of the insulating body being threaded upon these surfaces, as illustrated at 4, so that the two interrupted surfaces will together receive and hold the threaded base of an incandescent lamp, or the threaded conducting shell 5 of any threaded plug, such as the ordinary Benjamin swivel plug 6 illustrated in Fig. 4, and of which detailed description is unnecessary.

At the gaps in the threaded interrupted cylindrical surface 3 the cavity 2 is extend-

ed laterally in opposite directions, as indicated at 7 and 8, these two non-circular cavity extensions together forming a non-circular socket or seat to receive a non-circular push plug. This push plug may be of any desired form, and in Fig. 3 is illustrated as one of the standard rectangular push plugs, having an insulating body portion 9 provided with a central opening 10 to receive the lead wires, and having two of its opposite side walls provided with metal contacts 11 carrying the binding screws 12 to which the lead wires are secured.

The cylindrical portion of the cavity 2 is eccentric to its non-circular or rectangular portion. In other words, one of the cavity extensions is longer than the other, and in the present device cavity 8 is illustrated as longer than cavity 7, the purpose of which will now appear. Each of the cavities 7 and 8 contains a contacting member, the two members being alike except as hereinafter noted. Each contact includes a stationary body portion 13 lying inside the cavity and carrying a flexible resilient portion 14 in the form of a leaf spring, extending out into the cavity and preferably attached to the upper end of the body so that said spring is inclined downwardly toward the center of the cavity. The body portion 13 is suitably arranged for connection of a lead wire thereto, such as by being connected to a screw 15 passing through the body portion 1 and provided on the outside thereof with the nuts 16 for connecting the lead wires.

When the non-circular or rectangular plug, shown in Fig. 3 is pushed into the cavity 2 its two contacts 11 engage the two spring contacts 14 of the socket, thereby establishing connection from the lead wires running to the socket through said socket and plug to the lead wires of the plug. The plug may be pushed in in either of two positions, it being unnecessary to make any distinction as to which contact 11 engages a particular contact 14.

Since the cavity 8 is longer than the cavity 7 the spring contact 14 in cavity 8 is farther from the axis of the interrupted cylindrical surface 3 than the contact 14 in cavity 7. The parts are so proportioned as to take advantage of this construction to the end of preventing contact of the threaded shell 5 of a threaded plug with the contact 14 in cavity 8. Consequently when the plug is screwed in its threaded shell is connected

- to only one side of the socket circuit. Suitable provision must also be made to connect the end contact 17 of the plug with the other side of the socket circuit. This result may 5 be secured in any desired manner, preferably by providing a spring contact located in the bottom of the socket connected to the other side of the socket circuit. In the particular form shown the result is secured by 10 providing the contact 14 in cavity 8 with an extension 18 whose end portion lies in the axis of the threaded cylindrical surface 3. When the threaded plug is screwed in its end contact engages the extension 18 and 15 completes electrical connections to the plug. The presence of this extension does not, however, interfere with the use of the rectangular plug shown in Fig. 3.

The short contact 14 which engages the 20 threaded shell of a threaded plug may also have a portion of its spring leaf member corrugated, as at 20, to provide additional contacting surface for engagement with the threads of the threaded shell, although this 25 is not essential.

The socket described may be used interchangeably with a threaded screw plug or a non-circular push plug and therefore does away with the use of separate intermediate 30 adapters.

What I claim is:—

1. A chambered socket of the character described, provided in its chamber with

means for receiving and establishing electrical connections to either a threaded plug 35 or a non-circular push plug.

2. A socket of the character described, provided with a cavity shaped to receive interchangeably a cylindrical or non-circular plug, and means in said socket for establishing electrical connections to either of 40 said plugs.

3. A socket of the character described, comprising a body portion of insulating material having a cavity provided with a 45 non-circular wall and an interrupted cylindrical wall, and contacts in said cavity.

4. A socket of the character described, comprising a body portion of insulating material having a cavity provided with a non- 50 circular wall and an interrupted cylindrical wall, and contacts in said cavity, one of said contacts being farther from the axis of the cylindrical surface than the other.

5. A socket of the character described, 55 comprising a body portion of insulating material having a cavity provided with a non-circular wall and an interrupted cylindrical wall, contacts in said cavity, one of said contacts being farther from the axis of cylindrical surface than the other, and a contact near the axis of said cylindrical surface electrically connected to said first named contact.

In testimony whereof I affix my signature.
WILLIAM HALTER.
